G. A. SMITH

CUSHION

Filed Oct. 17, 1922

FIG. 1

UNITED STATES PATENT OFFICE.

GEORGE A. SMITH, OF LOS ANGELES, CALIFORNIA.

CUSHION.

Application filed October 17, 1922. Serial No. 595,023.

To all whom it may concern:

Be it known that I, GEORGE A. SMITH, a citizen of the United States, and resident of Los Angeles, county of Los Angeles, State 5 of California, have invented new and useful Improvements in Cushions, of which the following is a specification.

This invention relates to cushions, and more particularly to cushions for upholstered furniture such as davenport, chairs, 10 and the like.

It is the object of the invention to provide a readily detachable fastening connection for fixing a cushion in position upon a 15 seat.

A further object of the invention is to provide for retaining a cushion in proper position upon a seat, while making possible a limited movement at the front edge of the 20 cushion relative to the seat, in order to give the appearance of a loose cushion.

It is a still further object of the invention to removably secure a cushion upon a seat by means which will be normally completely concealed, but which will be readily accessible when fixing the cushion in position.

Further objects of the invention will be readily understood from the following description of the accompanying drawings, in 30 which:

Fig. 1 is a front elevation of a davenport having cushions constructed in accordance with the invention.

Fig. 2 is a top plan of the davenport, 35 showing one of the cushions removed, and one of the cushions in position for engaging the separable fastening means.

Fig. 3 is a detail section on the line 3—3 of Fig. 2.

Fig. 4 is a fragmentary section showing 40 one of the detachable fastening connections.

The invention is illustrated in connection with a usual upholstered davenport having the back A, arms B, front C, and seat D. 45 The cushions E, which may be three in number, are adapted to be received upon the seat, as illustrated in Fig. 2, showing the center cushion in place.

The davenport has a usual ornamental 50 outer cover 1 upon the back, arms, and front of the same. The upper edge of the cover for the front of the davenport seat extends for a short distance over the roll F which is formed at the junction of front C and seat 55 D, and said extension is fixed to the seat

cover 2 so as to provide a finishing cover 1^a at the front portion of the seat. This construction is illustrated at the right of Fig. 2 showing the right hand cushion removed.

Each cushion has an ornamental outer cover 3 on the top and sides thereof, and said cover at the front of the cushion is extended at its lower edge to form a flap 5. The flap may have a reinforcing backing 6 of buckram or the like, fixed thereto, in order to form a relatively stiff flap.

The flap is fixed to the underside of the cushion in spaced relation from the end of the flap and adjacent the front of the cushion, as by the stitching 7, said flap being thereby adapted to normally lie against the underside of the cushion at the front portion of the same, but being readily swingable relative to the cushion.

Means are provided for detachably connecting the flap 5 to the seat D, with the cushion adapted to overlie said flap and rest upon the seat, said connection thereby retaining the cushion in proper position upon the seat.

The connecting means may consist of eyelets 8 inserted in the seat D, and heads 9 adapted to be snapped into said eyelets and carried by the flap 5 in spaced relation from the stitching 7 and adjacent the free end of said flap.

The heads 9 are upon the side of flap 5 which is toward the seat when the flap is in normal position against the underside of the cushion, and the cooperating heads and eyelets are so positioned that when engaged, the cushion will be properly placed upon the seat.

The separable fastening connection as thus described will hold the cushion against forward shifting on the seat, and abutment of the cushion against the back of the davenport will hold the cushion against rearward shifting. When backing 6 is fixed to the flap, the resulting stiffened flap will provide additional means for holding the cushion against rearward shifting when the fasteners are connected.

The heads 9 being positioned at the free movable portion of flap 5 and in spaced relation from stitching 7, the extreme front portion of the cushion is free for limited vertical movement on the seat when the fasteners are engaged; and a usual crack or space may thus be formed between the

2 cushion and seat at the front of the same, in order to give the appearance of a cushion loosely placed upon the seat. At the same time, the cushion will be retained in proper position by the fastening connections, and the latter will prevent the cushion moving away from the seat to such an extent as to expose the unfinished underside of the cushion beyond the flap, or the unfinished 10 cover 2 of the seat beyond the extension 1^a of the ornamental outer cover.

With the construction as thus set forth, it will be noted that the fastening means are completely concealed when the cushion 15 is in place upon the seat of the davenport, and in order to remove the cushion it is simply necessary to pull upon the same with sufficient force to disengage the separable fasteners 8—9.

20 When placing the cushion upon the seat, the cushion is turned over as shown at the left of Fig. 2 and in Fig. 3, with flap 5 swung away from the cushion. The cushion is then positioned with the out-turned flap 25 above the front portion of the seat so that the fastening connections are readily accessible for snapping the heads 9 into the eyelets 8. When the fasteners have been engaged, the cushion is swung down over 30 the flap and onto the seat, in proper position upon the davenport.

While I have illustrated and described the invention in connection with a davenport, it will be apparent that the invention 35 is applicable to a cushion structure for use upon any seat.

I claim as my invention:

1. The combination with a seat of a removable cushion adapted to be mounted 40 thereon, said cushion having an ornamental cover forming a flap extension at the lower front edge of the cushion, with said flap fixed to the underside of said cushion adjacent the front of the latter, and forming 45 a free swinging portion adapted to extend rearwardly beneath said cushion for concealing the flap between the cushion and seat, and cooperating separable fastening connections on the top of the seat in spaced 50 relation from the front thereof, and upon the free swinging portion of said flap, whereby said cushion may be removably fixed in position upon said seat, while permitting spaced relation between the fronts 55 of said seat and cushion, and exposing said

spaced relation to simulate the appearance of a cushion loosely mounted on a seat.

2. The combination with a seat of a cushion, said cushion having a flap forming a free swinging portion adapted to extend 60 between the cushion and seat, means for fastening the free swinging edge of said flap to the top of said seat for fixing the cushion in position against movement in one direction relative to said seat, said flap having reinforcing stiffening means to prevent buckling thereof so as to fix the cushion in position against movement in the opposite direction relative to said seat, said fastening means permitting spaced relation between the front of said cushion and seat, and exposing said spaced relation to simulate the appearance of a cushion loosely mounted on a seat. 70

3. The combination with a seat of a 75 cushion having a flap fixed to the underside thereof adjacent the front of the cushion and forming a free swinging portion adapted to extend rearwardly between said cushion and seat, and means for fastening the free swinging edge of said flap to the top of the seat in spaced relation from the front thereof, whereby said cushion is fixed in position upon said seat while permitting spaced relation between the front of said 80 seat and cushion, and exposing said spaced relation to simulate the appearance of a cushion loosely mounted on a seat. 85

4. The combination with a seat of a cushion having a flap fixed to the underside 90 thereof and forming a free swinging portion adapted to extend between the cushion and seat, and means for fastening the free swinging edge of said flap to the top of said seat for fixing the cushion in position against movement in one direction relative to said seat, said flap having reinforcing stiffening means to prevent buckling thereof so as to fix the cushion in position 95 against movement in the opposite direction relative to said seat, said fastening means permitting spaced relation between the front of said cushion and seat, and exposing said spaced relation to simulate the appearance of a cushion loosely mounted on a seat. 100

In testimony wherof I have signed my name to this specification.

GEORGE A. SMITH.
